RAILWAY TRUCK

Donald S. Barrows, Rochester, N. Y., assignor to
 The Symington-Gould Corporation, Rochester,
 N. Y., a corporation of Maryland

Application September 5, 1934, Serial No. 742,825

13 Claims.

(Cl. 267—4)

This invention relates to railway trucks and, more particularly, to nests of springs for supporting truck bolsters with spring plates for said nests.

5 The principal object of my invention, generally considered, is to provide a practical interlock between all of the springs, in a nest of helical and elliptic or leaf springs, without making it necessary to assemble the entire spring group in the truck at one time.

Another object of my invention is the provision of a nest of helical and elliptic or leaf springs with two main cast plates and two auxiliary plates, each cast plate engaging two coils or helical spring units only and an elliptic spring band, and each auxiliary plate connecting only two coils or helical spring units.

20 A further object of my invention is the provision of a nest of helical or coil and elliptic or leaf springs, in which the top and bottom main plates extend from opposite sides of the group, that is, the lower plate preferably extends outwardly from the inner side of the group and the upper plate preferably extends inwardly from the outer side of the group, said plates being supplemented by auxiliary plates which span helical or coil springs only.

25 A still further object of my invention is the provision of a novel method of assembling a nest of helical or coil and elliptic or leaf springs comprising, first, the application of two coils with an upper auxiliary plate to the bottom main plate, second, the application of the lower half of the elliptic spring or lower semi-elliptic spring portion to said lower main plate, third, the application of the inner elliptic spring end or block, fourth, the application of the top half of the elliptic spring or upper semi-elliptic spring, fifth, 40 the application of the two outer coils or helical spring units with the associated upper main plate and lower auxiliary plate, and sixth, the application of the outer elliptic spring end or block.

45 Other objects and advantages of the invention relating to the particular arrangement and construction of the various parts will become apparent as the description proceeds.

50 Referring to the drawings illustrating my invention, the scope whereof is defined by the appended claims:—

Figure 1 is a fragmentary side elevational view of a railway truck embodying my invention.

55 Figure 2 is a transverse sectional view of the spring nest removed from the truck, and taken

on the line 2—2 of Figure 1, looking in the direction of the arrows.

Figure 3 is a plan of the nest of springs shown in Figure 2.

Figure 4 is a detail plan of one of the main 5 spring plates.

Figure 5 is a vertical sectional view on the line 5—5 of Figure 4, looking in the direction of the arrows.

Figure 6 is a detail sectional view, partly in elevation, on the line 6—6 of Figure 4, looking in the direction of the arrows.

Figure 7 is a detail plan of one of the auxiliary spring plates.

Figure 8 is a sectional view, partly in elevation, 15 on the line 8—8 of Figure 7, looking in the direction of the arrows.

Referring to the drawings in detail, like parts being designated by like reference characters, there is shown a portion of a railway truck 1 involving a pair of side frames 2, only one of which is illustrated, receiving the ends of a bolster 3, only one end of which is illustrated. The bolster 3 extends into the windows 4 of the frames 2, each window being defined by a compression member 5, a tension member 6, and bolster guide columns 7. Supported at each end, on the tension member of the frame beneath the windows 4, is a spring plank 8 between each end of which and each corresponding end of the bolster 3 is a nest of springs 9 disposed in the corresponding windows 4.

Each nest of springs 9 comprises, in the present embodiment, four helical or coil springs or spring units 10 and an elliptic or banded leaf spring, or series of leaf springs held together by bands, 11. Each spring 11 in the present embodiment comprises a stack or series of curved spring leaves 12 held together intermediate their ends by bands 13, and divided into upper and lower 40 groups, with their end portions separated by blocks or end members 14, in accordance with the usual practice for full elliptic springs.

In order to center or hold the elliptic and coil springs in proper position between the bolster 45 and spring plank, or bolster and frame, if the spring plank is omitted, I employ a pair of main, preferably cast, and interchangeable, upper and lower spring caps or plates 15 and 16, said plates being formed to surround or partially house the 50 spring bands, as well as being provided with collars or spring centering portions 17 extending toward the collars or corresponding portions 18 of associated auxiliary, preferably pressed metal, spring plates 19 and normally surrounded by the 55

associated coil or helical springs 10 for centering purposes. The main spring plates 15 and 16 also directly engage the adjacent ends of the coil springs and are, in the present embodiment, thicker at these places than the remaining web portions of the plates, thereby providing elevating seats for said springs which are closer to one another than the seats for the elliptic spring bands, one of which is formed on each main spring plate, thereby avoiding overstressing the leaves of said elliptic spring, or allowing for the greater travel of said spring than would otherwise be permissible.

The construction of each main spring plate is desirably as illustrated in Figures 4, 5 and 6.

The spring band seating portion 20 desirably comprises a lower web portion 21 which is concave upwardly, thereby insuring that the edge portions of the associated spring band engage said plate to avoid wobbling or rocking. The web portion 21 is bounded by flange portions 22 extending in the same direction as the helical spring centering portions 17, said flange portions being of a height less than the thickness of the spring band material where they extend across the spring leaves, and higher at the sides of said spring leaves, as indicated at 23, so that each spring band and its associated leaves forming a semi-elliptic spring is positioned by flanges which not only engage the sides of the band, but also the outermost spring leaf, thereby insuring the proper centering or positioning of the associated elliptic spring.

The helical spring positioning portions 17 and 18 are, in the present embodiment, formed so that they center the coils of the spring units 10, shown in the present embodiment as single coil, although inner coil springs may also be used, if desired. The spring centering portions 18 of the auxiliary plates 19 are, in the present embodiment, formed tapered or conical, with the springs 10 centered about the base portions of said bosses. The centering bosses of the cast or main plates 15 and 16 are shown as of a form which is not truly conical, but which provides for centering the helical springs 10 on the pedestals 26 of the bosses 17. Assembly of the main and auxiliary spring plates is desirably effected by normally vertical bolts 28 and associated securing nuts 29 passing through the corresponding centering bosses 17 and 18 and desirably positioned coaxially with the helical springs, as will be seen from an inspection of Figure 2.

In order to minimize weight, the spring centering portions 17 of the cast plates are desirably ribbed rather than solid, as shown most clearly in Figure 4, said ribbing 26 desirably merging with ribbing 30 around the remaining peripheral portions of the plate. The ribbing 30 serves to connect the separated ribbing portions 26 and said ribbing portions to the spring band centering ribbing or flanges 22. It will thus be seen that the coils 10 are supported on relatively low serpentine ribbing portions 26 around the relatively high radially extending ribs or spoke portions 25. Spring plate centering or positioning nibs 31 on the main and 32 on the auxiliary spring plates are desirably provided and adapted to fit in corresponding pockets in the associated bolster, frame, or spring plank, if used.

The springs, spring plates and securing bolts are desirably assembled with the side frame, bolster and spring plank, if used, as follows:—After the spring plank and bolster 3 are assembled 75 with respect to the frame 2, and with the bolster

elevated in the window 4, the two inner coils or helical spring units 10 are assembled on the main bottom plate 16. The top auxiliary plate for these springs and the securing bolt 28 are then applied, after which the lower half of the elliptic spring 11 is positioned with its spring band 13 resting on the supporting web 21 and surrounded by the flange portions 22 and 23. The inner spring end or block 14 is then applied, after which the top half of the elliptic spring 11 is positioned with its inner end engaging said inner block 14, with the outer block 14 temporarily omitted. The next step is to assemble the two outer coil spring units 10 with the top plate 15 and the bottom auxiliary plate 18 connected by the associated bolt 28, and position these assembled parts with the top elliptic spring band positioning portion disposed over said spring band. The final step is to raise the upper half of the elliptic spring by positioning the outer block 14 and causing the upper band 13 to fit the downwardly opening pocket in the upper spring plate 15 provided for the purpose. The assembly being complete, the bolster may be lowered to position thereon. When it is desired to remove the spring assembly from the truck, the parts are taken out in the reverse order, as will be understood.

Although a preferred embodiment of my invention has been illustrated and described, it will be understood that modifications may be made within the spirit and scope of the appended claims.

I claim:—

1. A spring nest, adapted for insertion in the window of a railway vehicle side frame for the support of an associated bolster, comprising outer and inner rows of helical springs with an elliptic spring spanning the distance therebetween, a lower spring plate supporting and positioning only the inner row of helical springs and the elliptic spring, a lower spring plate supporting and positioning only the outer row of helical springs, an upper spring plate resting only on the outer row of helical springs and said elliptic spring, and an upper spring plate resting only on the inner row of helical springs.

2. A spring nest, adapted for insertion in a window of a railway vehicle side frame for the support of an associated bolster, comprising outer and inner rows of helical springs with an elliptic spring resting therebetween; said nest having main upper and lower spring plates, one of which positions the outer helical springs only and has a portion extending to position the adjacent band of the elliptic spring, and the other of which positions the inner helical springs only and has a portion projecting to position the adjacent band of the elliptic spring, and auxiliary spring plates, one of which positions only the outer helical springs and the other of which positions only the inner helical springs.

3. A spring nest, adapted for insertion in the window of a railway vehicle side frame for the support of an associated bolster, comprising a pair of outer helical spring units, a pair of inner helical spring units, an elliptic spring resting between said units, a lower cast spring plate supporting and positioning only the inner pair of helical units, and formed with a portion on which the lower band of the elliptic spring seats, an upper cast spring plate resting only on the outer helical spring units, and formed with a portion projecting to seat on the upper band of the elliptic spring, and auxiliary pressed metal 75

- spring plates seating only on the helical springs and supplementing the cast spring plates.
4. A spring nest, adapted for insertion in the window of a railway vehicle side frame for the support of an associated bolster, comprising outer and inner rows of helical springs with a spring comprising resilient leaves spanning the distance therebetween, a lower spring plate supporting and positioning only the inner row of helical springs and engaging and interlocking with a portion of the leaf spring, a lower spring plate supporting and positioning only the outer row of helical springs, an upper spring plate resting only on the outer row of helical springs and engaging another portion of said leaf spring, and an upper spring plate resting only on the inner row of helical springs.
5. A nest of helical and banded leaf springs comprising two main plates and two auxiliary plates, each main plate engaging two helical spring units only and a band of said leaf spring, and each auxiliary plate connecting only two helical spring units.
6. A nest of springs comprising coil and banded leaf springs and spring plates in which top and bottom main plates extend from opposite sides of the nest from corresponding coil springs to interlock with the same leaf spring, and supplemental plates associated with the remaining ends of the coil springs only.
7. A spring nest, adapted for insertion in the window opening of a railway vehicle side frame for the support of an associated bolster, comprising a pair of outer helical spring units, a pair of inner helical spring units, an elliptic spring resting between said units, a lower spring plate supporting and positioning only the inner pair of helical units and formed with a portion supporting and interlocking with the elliptic spring, an upper spring plate resting only on the outer helical spring units and formed with a portion engaging and interlocking with the elliptic spring, auxiliary spring plates engaging the helical springs only and supplementing said lower and upper plates, and means passing through corresponding plates along the axes of the helical spring units for holding said plates in assembled position.
8. A nest of coil and leaf springs formed in three parts, first, a leaf spring comprising upper and lower bands for the leaves thereof, second, a nest of coil springs having an upper cap with an extension interlocking with the upper spring band, and third, a nest of coil springs having a lower spring cap with an extension interlocking with the lower spring band.
9. A nest of springs comprising coil and banded leaf springs and spring plates, in which the top and bottom plates extend from opposite sides of the nest from corresponding coil springs to interlock with the same leaf spring.
10. A cast plate for a nest of springs comprising radial rib portions adapted to center a coil spring and serpentine rib portions, the inner bends of which merge with the outer ends of said radial rib portions, said serpentine rib portions forming reinforcements on the spring-engaging side of said plate and providing a seating surface for a coil spring.
11. A cast plate for a nest of springs comprising radial rib portions adapted to center a coil spring and serpentine rib portions, the inner bends of which merge with the outer ends of said radial rib portions, said serpentine rib portions forming reinforcements on the spring-engaging side of said plate and providing a seating surface for a coil spring, the inner ends of said radial ribs merging with an embossment apertured to receive means for securing said plate to one associated with the other end of said coil spring.
12. A nest of springs comprising banded leaf springs forming an elliptic spring and coil spring means comprising at least one coil spring on each side thereof, a spring plate for the lower elliptic spring band and the coil spring means on one side only of said elliptic spring, and a spring plate for the upper spring band and the coil spring means on the other side only of said elliptic spring.
13. A nest comprising a set of banded leaf springs and at least one helical spring on each side of said set, and two spring plates, one of which engages only one end of the helical spring means at one side of the leaf springs and a band thereof, and the other of which engages the other end of the helical spring means at the other side of the leaf springs and another band thereof.

DONALD S. BARROWS. 50
